ATTORNEY.

UNITED STATES PATENT OFFICE

HARRY KLEINBERG, OF PITTSBURGH, PENNSYLVANIA

SHIRT

Application filed January 29, 1932. Serial No. 589,726.

This invention relates to outer shirts.

Very often shirts come back from the laundry with the walls of the pockets in the neckband into which the collar button is inserted so starched together that it is practically impossible to pry the walls apart except by a sharp instrument. It is therefore the main object of the invention to provide means to easily separate the walls of the pockets in the neckband which house the base of the collar button when the said walls are starched together.

Another object of the invention is to provide a shirt having a tab attached to one of the walls of the pockets in the neckband for housing the collar button, said tab adapted to pull the walls apart for inserting the collar button.

Other objects will appear as the disclosure progresses. The drawing is intended to merely indicate a possible embodiment of the invention. It is obvious that the actual needs of manufacture may necessitate certain mechanical changes. It is therefore not intended to limit the invention to the embodiment illustrated but rather to define such limits in the appended claims. For a more general understanding of the invention attention is called to the drawing. In this drawing like reference characters denote like parts throughout the specification.

In the drawing:

Figure 1 is a front view of a dress shirt partly open and showing the tabs attached to the neckband.

Figure 2 is an enlarged section on line 2-2 of Figure 1.

Figure 3 is a view looking at the neckband in the direction of arrow A of Figure 1.

Figure 4 is a view of a dress shirt having a stiff bosom showing the tabs in place.

Figure 5 is a section on line 5-5 of Figure 4.

Figure 6 is a section on line 6-6 of Figure 4 and

Figure 7 is a shirt with the collar attached showing the tab in place.

Referring now to the drawing in detail numeral 1 designates the shirt, 2 the neckband and 3 the button-holes therein. Formed in

the neckband is a pocket 4 for housing the base of the collar button 5. The front wall 6 of the pocket corresponds to the front of the neckband and the back wall 7 of the back corresponds to the inside of the neckband. The wall 6 as indicated in Figure 2 is of double thickness and inserted between the said walls is a tab 8 of double thickness. The tab extends up to the button-hole 3 and the top edge of the said tab is sewed to the button-hole by the usual overcast stitches 9. The central part of the tab is sewed to the edge of the wall 6 by the stitches 10. The tab is made of soft material so it can easily be used for opening the pocket 4 should the walls 6 and 7 be starched together.

In Figure 4 is shown a stiff bosom dress shirt with the tabs attached to the front and back pockets of the neckband. Numeral 11 designates the shirt, 12 the neckband and 13 the pockets for holding the collar buttons 14. Attached to one of the walls of the pockets are the tabs 15. These tabs are the same and function similar to the tabs 8.

Figure 7 shows the tab used in connection with a shirt with an attached collar. Numeral 16 designates the shirt, 17 the neckband and 18 the tab. This tab is attached in the same manner as the tab 8 shown in Figure 1.

It will thus be seen that I have provided an efficient, economical and simple means for separating the walls of the pockets when starched together for inserting the collar button. Having described my invention, I claim:

1. In a shirt of the class described in combination, a neckband having two walls forming pockets between them for the insertion of a collar button, one of said walls provided with a button-hole, said last mentioned wall formed of two thicknesses of material, a tab held between said two thicknesses of material, the top edge of said tab sewed in the overcast stitches of said button-hole.

2. In a shirt of the class described in combination, a neckband having two walls forming pockets between them for the insertion of a collar button, one of said walls provided with a button-hole, overcast stitches around the inside edge of said button-hole, said last

mentioned wall formed of two thicknesses of material, a tab held between said two thicknesses of material, said tab made of two thicknesses of material, the top ends of both thicknesses of said tab sewed in the overcast stitches of said button-hole.

3. In a shirt of the class described in combination, a neckband having two walls forming pockets between them for the insertion of a collar button, one of said walls provided with a button-hole, overcast stitches around the inside edge of said button-hole, said last mentioned wall formed of two thicknesses of material and having inturned edges, a tab held between said two thicknesses of material and inturned edges, said tab made of two thicknesses of material, the top ends of both of said thicknesses of material of said tab sewed in the said overcast stitches of said button-hole, and another row of stitches for sewing the central part of the tab between said last mentioned wall formed of two thicknesses of material.

4. In a shirt of the class described in combination, a neckband, having two walls forming pockets between them for the insertion of a collar button, one of said walls provided with a button-hole, overcoat stitches around the inside edges of said button-hole, a tab made of two thicknesses of material, the top ends of both thicknesses of material of said tab sewed in the overcast stitches of said button-hole, and another row of stitches for sewing the central part of said tab to one of the said walls of the neckband.

In testimony whereof I affix my signature.
HARRY KLEINBERG.
